FLY CASTING FISHING REEL

Jean-Paul Lemery, Cluses, France, assignor to Etablissements Carpano et Pons, Cluses, France

Filed Sept. 29, 1971, Ser. No. 184,986

Term of patent 14 years

Int. Cl. D22—05

U.S. Cl. D22—25

FIG. 1 is a side elevation view, viewed from the spool side, of a fly casting fishing reel, showing my new design;

FIG. 2 is a side elevation view of the opposite side thereof;

FIG. 3 is a bottom view thereof;

FIG. 4 is a top view thereof; and

FIG. 5 is a front elevation view thereof, viewed from the right hand side of FIG. 1.

I claim:

The ornamental design for a fly casting fishing reel, as shown.
